UNITED STATES PATENT OFFICE.

CHARLES O. L. CARDELL, OF PEARL RIVER, NEW YORK, ASSIGNOR TO DEXTER FOLDER COMPANY, OF PEARL RIVER, NEW YORK, A CORPORATION OF NEW YORK.

PAPER-FEEDING MACHINE.

1,057,116.

Specification of Letters Patent. Patented Mar. 25, 1913.

Application filed August 30, 1911. Serial No. 646,901.

To all whom it may concern:

Be it known that I, CHARLES O. L. CARDELL, a citizen of the United States, and a resident of Pearl River, Rockland county, 5 State of New York, have invented certain new and useful Improvements in Paper-Feeding Machines, of which the following is a specification.

The present invention relates to improvements in the type of paper feeding machines known as continuous feeders, in which inclined supply and feed tables are supported one above the other, with a curved throat or passageway communicating between them 15 at their rear ends. With this type of feeder, a continuous pile of sheets, supplied from time to time upon the supply table, is fed by suitable mechanism through said curved throat to the feed table and presented in combed-out condition upon the feed table 20 for the action of any suitable sheet feeding devices which convey the sheets singly to the printing press, folding machine or other machine arranged to operate upon them.

The present invention consists of a new 25 form of feeding mechanism for this type of machine by which the feeding of the combed-out bank of sheets from the supply table to the feed table is more positively accomplished.

The invention comprises a feed drum or a series of feed pulleys mounted between the rear ends of the supply and feed tables so as to form the inner surface of the curved 35 communicating throat, and an automatically controlled pile clamping device mounted to engage the rear surface of the curved bank of sheets and clamp the bank of sheets against the feed drum or pulleys and move 40 with the drum or pulleys while the bank is clamped against them to positively feed the bank of sheets through said throat.

In order that the invention may be fully understood, I will first describe the same 45 with reference to the accompanying drawings, and afterward point out the novelty more particularly in the annexed claims.

In said drawings Figure 1 is a partial side elevation of a paper feeding machine 50 having my improvements applied thereto, Fig. 2 is a plan view of the same with the parts broken away, Fig. 3 is an enlarged detail vertical longitudinal sectional view of the main parts of the improved feeding 55 mechanism, Fig. 4 is a detail sectional plan

view of part of the same, Fig. 5 is a detail plan view of a part of one of the main feeding levers, Fig. 6 is a view similar to Fig. 3 showing the parts in shifted position, and Fig. 7 is a detail side elevation of one of the 60 U-shaped rocking levers which connect the main operating levers with the rocking frame.

In the accompanying drawings, 1 is a supply table mounted in inclined position 65 upon suitable side frames indicated at 2, and 3 is a feed table mounted directly beneath the supply table between the side frames 2. The supply table 1 is inclined downwardly toward its rear end, while the 70 feed table 3 is inclined downwardly toward its front end.

5 is a transverse shaft journaled at its opposite ends in the side frames 2 and supporting within the side frames a cylindrical feed drum 6. The drum 6 may be in the form of a plurality of feed wheels or pulleys, although the drum formation is preferred. The feed drum 6 is mounted between the supply table 1 and feed table 3 80 at their lower ends so as to form the inner curved surface of the usual throat which communicates between said tables, the upper surface of drum 6 being practically a continuation of the surface of table 1, while 85 the lower surface of drum 6 is supported sufficiently above the surface of the feed table 3 to allow for the passage of a bank of sheets from the curved throat to the feed table 3.

Passing longitudinally over the inclined supply table 1 are the heavy endless feed belts 10, which pass around the supporting pulley 11 and driving pulley 12. The supporting pulley 11 is mounted upon a shaft 13 which is journaled in brackets 14 secured beneath the supply table 1. The driving pulley 12 is mounted upon a shaft 15 journaled in brackets 16 also secured beneath the table 1. A tension and guiding pulley 17 is mounted upon a transverse shaft 18 journaled in brackets 19 beneath the table 1. Keyed to the shaft 15 is a gear wheel 20 which meshes with an intermediate gear 21 journaled upon a bracket arm 22 and driven 105 by a large gear 23 secured to one end of the feeding drum 6. Passing longitudinally over a portion of the lower feed table 3 is a series of heavy feeding belts 25 which are mounted upon the supporting and driving 110

pulleys 26 and 27 mounted respectively on transverse shafts 28 and 29 suitably journaled in brackets secured beneath the table 3. The belts 25 pass over the tension and 5 guiding pulley 30 journaled in and supported by brackets 31. The shaft 29 has keyed to it a gear wheel 35 which is driven through the intermediate gears 36 and 37, the latter of which meshes with the large gear 23 upon the end of drum 6.

From the described mechanism, it will be observed that the upper carrying portion of the belts 10 and 25 will have feeding motion imparted to them whenever the drum 6 15 is rotated. Curved guides indicated at 40 are mounted at 40° upon the rear end of the feed table 3 and extend therefrom parallel with the surface of the feed drum 6 to a point above the rear end of the supply table 1. These curved guides 40 form with the feed drum 6, the curved throat which communicates between the supply table 1 and feed table 3.

Journaled upon the opposite ends of the 25 shaft 5 are the upwardly presented rock arms 45 connected at their upper ends by a transverse bar 46 which forms with said rock arms a rocking frame. One of the rock arms 45 has journaled upon it at 50 30 a dog or pawl 51 which rests in operative relation to a large ratchet wheel 52 secured to the end of drum 6 opposite to the large gear 23.

The transverse shaft 55 is mounted in, and 35 extends between, the upright rock arms 45 journaled upon the shaft 55 just outside of the rock arms 45 and along curved floating operating levers 60 which are firmly joined together by a transverse rod or bar 40 61 which carries two or more curved clamping plates 62 which are supported in operative relation to the outer surface of the curved portion of a feathered-out pile of sheets in its passage from the supply table 45 1 to the feed table 3. The curved clamps 62 are designed to engage the curved section of the pile of sheets adjacent to the stationary curved guides 40 above referred to.

Each of the curved levers 60 is formed at 50 its upper end with a forwardly projecting foot 65 which rests between the adjustable tappet screws 66 mounted respectively in the upper and lower arms 70^a and 70^b of an approximately U-shaped rock arm or lever 55 70 which is journaled at 71 upon the transverse shaft 55 just inside of one of the upright rock arms 45. The arms 70^a and 70^b extend forwardly and laterally from the journal bearing 71 so as to present tappet screws 66 60 in the same vertical plane as the foot 65. An adjustable stop screw 67 is threaded through a lug 70^c of rock arm 70 in position to engage the forward face of one of the rock arms 45 to limit the movement of 65 rock arm 70 with relation to rock arm 45.

The described connection between lever 60 and rock arm 45 through rock arm 70 is the same at both sides of the machine.

The lower end of each of the floating levers 60 has pivoted to it at 75 a pitman 76 formed at its forward end with a guide loop 77 operating over a cam shaft 78 carrying an operating cam 79 which engages an anti-friction roller 80 journaled upon the looped end of pitman 76. A tension rod 85 is 75 pivoted to each floating lever 60 at 86 and extended forwardly from said pivot through a guide bracket 87 secured to the under face of the feed table 3. An expansion spring 88 surrounds the rod 85 and is confined against the bracket 87 by an adjustable collar 89 secured upon the rod 85. Each of the connected floating levers 60 may be actuated by a pitman 76 and tension rod 85 under the control of a cam 79, or if preferred, the operation can be effected by a single pitman and tension rod controlled by a single cam.

One of the pitmen 76 carries a block 90 formed with a stop notch 91 presented directly beneath a controlling dog 92 pivoted at 93 to a bracket 94 secured to the under face of feed table 3. A link 95 connects the dog 92 with a rock arm 96 secured to a rock shaft 97 journaled in bracket arm 98 extending upwardly from the feed table 3. The shaft 97 projects toward the central vertical longitudinal plane of the machine above the sheets upon the feed table 3. The inner end of rock shaft 97 carries a rock arm 96^a thrust downwardly by a spring actuated tension rod 99 and carrying in its forward end an anti-friction roller 100 which is designed to operate upon the surface of the sheets passing forwardly over the feed table 100 3. When the quantity of sheets upon the feed table 3, at the gaging point of the mechanism just described, is sufficiently close to normal, the position of the rock arm 96^a will hold the dog 92 in the path of the shoulder 91 so as to prevent the feeding 110 operation of the mechanism above described. As soon as the sheets pass forwardly from beneath roller 100 to a sufficient extent, the dog 92 will be raised out of the notch 91 115 to allow the resumption of the feeding operation.

At 105 I have shown more or less diagrammatically one of a plurality of sheet combing wheels which are designed to separate the sheets and feed them forwardly singly from the feed board 3 into convenient position to be taken by the machine which is to operate upon the sheets.

In operation, it will be understood that 125 the operator supplies the necessary sheets in combed-out position upon the supply table 1. Assuming the supply of sheets upon feed table 3 to have become sufficiently exhausted to require a further forward

ment of the combed-out blank of sheets, the dog 92 will have released the block 90 so that the cam 79 pulling forward upon the pitman 76 will first rock the levers 60 upon shaft 55 to firmly clamp the curved section of the combed-out bank of sheets between the clamps 62 and the surface of the drum 6. The continued pulling of pitman 76 acting through levers 60 will rock the connected rock arms 45 rearwardly causing dogs 51, through ratchet wheel 52, to rotate the drum 6 at the same time that the curved clamps 62 move downwardly so that the combed-out bank of sheets will be positively moved through the throat leading from the supply table to the feed table. At the completion of the described feeding stroke, the tension rods 85 will return the parts to normal position, the first action on this rearward movement being to move the clamps 62 away from the curved section of the bank of sheets to release the sheets from the clamping action, and then to move the ratchet-carrying rock arms back to their normal position ready for another feeding stroke.

What I claim is:

1. In a paper feeding machine, the combination of a support for a bank of sheets, with feeding mechanism acting upon the opposite surfaces of said bank of sheets and adapted to rigidly grip and release the bank of sheets said mechanism being movable with the entire bank for feeding the same.

2. In a paper feeding machine, the combination of a support for a bank of sheets with feeding mechanism including members arranged to intermittently and fixedly clamp a bank of sheets upon opposite surfaces and means operative during the clamping action of said members for moving said members together with the bank of sheets relatively to said support.

3. In a paper feeding machine, the combination of the supply and feeding tables, a throat or passageway communicating between said tables, and feeding mechanism movable along said throat and adapted to intermittently clamp a bank of sheets and feed the same through said throat or passageway.

4. In a paper feeding machine, the combination of a supply table, a feeding table supported thereunder, and a throat or passageway communicating between said tables, with intermittently operating feeding mechanism adapted to alternately clamp and release a bank of sheets in said throat or passageway for feeding the same therethrough.

5. In a paper feeding machine, the combination of the supply and feed tables supported one above the other, and a feeding drum mounted between the adjacent ends of the said tables, with oscillatory means for

intermittently clamping a bank of sheets against said feeding drum, and means for simultaneously moving said drum and clamping means for advancing the bank of sheets.

6. In a paper feeding machine, the combination of the supply and feed tables supported one above the other, and a feeding drum mounted between the adjacent ends of the said tables, with an oscillatory clamp adapted to grip a bank of sheets against said feeding drum, means for operating said clamp, and means for simultaneously moving said drum with said clamp for advancing the bank of sheets.

7. In a paper feeding machine, the combination of the supply and feed tables supported one above the other, and a feeding drum mounted between the adjacent ends of the said tables, feed belts operating over the surfaces of said tables, and means for driving said feed belts from said feeding drum, with means for clamping a bank of sheets against said feeding drum, and means for simultaneously moving said drum and clamping means for advancing the bank of sheets.

8. In a paper feeding machine, the combination of the supply and feed tables arranged with a sheet conveying throat or passageway communicating between their adjacent ends, a feed drum mounted between said tables and constituting the inner surface of said throat or passageway, pawl and ratchet mechanism for intermittently operating said feed drum, and oscillatory clamping means adapted to clamp a bank of sheets against said drum during its feeding action.

9. In a paper feeding machine, means for intermittently clamping a bank of sheets together, said means being adapted to impart a curvature to said bank of sheets, and means for imparting an angular movement to said clamping means corresponding to the curvature imparted to said bank.

10. In a paper feeding machine, the combination of the supply and feed tables supported one above the other, and a feeding drum mounted between the adjacent ends of said tables, an oscillating lever carrying a clamp which is adapted to grip a bank of sheets against said feeding drum, and means for simultaneously operating said lever and drum for advancing a bank of sheets.

11. In a paper feeding machine, the combination of a support for sheets, a feeding drum mounted adjacent to said support, a pivotally mounted rock arm, a lever pivoted upon said rock arm, a clamp carried by said lever and adapted to grip sheets against said feeding drum, and means for simultaneously operating said clamp and drum for advancing sheets.

12. In a paper feeding machine, the com-

- bination of a support for sheets, a feeding drum, a pivotally mounted rock arm, a lever pivoted upon said rock arm, a clamp pivoted upon said lever and adapted to grip sheets against said feeding drum, and means for simultaneously operating said clamp and drum for advancing sheets.
13. In a paper feeding machine, the combination with curved guides for producing a combing out of a bank of sheets, of means for intermittently clamping said sheets together, said means being movable angularly to correspond with the curvature of said guides.
14. In a paper feeding machine, the combination of a support for sheets, a rotary feeding member mounted adjacent to said support, a floating pivoted lever, a clamp mounted upon said lever in position to grip sheets against said rotary feeding member, operating means connected with said lever and means actuated by said lever for operating said rotary feeding member simultaneously with the movement of said lever.
15. In a paper feeding machine, the combination of the supply and feed tables arranged with a sheet conveying throat or passageway communicating between their adjacent ends, a feed drum mounted between said tables and constituting the inner surface of said throat or passageway, pawl and ratchet mechanism for intermittently operating said feed drum, clamping means adapted to clamp a bank of sheets against said drum during its feeding action, and operating means for simultaneously operating said pawl and ratchet mechanism and clamping means.
16. In a paper feeding machine, the combination of a supply and feed table having a sheet conveying throat communicating between them, a feeding drum mounted between said tables at the inner side of said throat, a ratchet wheel mounted upon said drum, a rock arm carrying a dog which engages said ratchet wheel, a floating lever pivotally connected with said rock arm, a clamp carried by said floating lever, and means for operating said lever.
17. In a paper feeding machine, the combination of a supply and feed table having a sheet conveying throat communicating between them, a feeding drum mounted between said tables, a ratchet wheel mounted upon said drum, a rock arm carrying a dog which engages said ratchet wheel, a floating lever pivotally connected with said rock arm, means limiting the pivotal movement of said floating lever upon said rock arm, a clamp carried by said floating lever, and means for operating said lever.
18. In a paper feeding machine, the combination of the supply and feed tables arranged with a sheet conveying throat or passageway communicating between their adjacent ends, a feed drum mounted between said tables, pawl and ratchet mechanism for intermittently operating said feed drum, a rock arm operating said pawl and ratchet mechanism, a curved lever pivotally mounted upon said rock arm, a clamp pivotally mounted upon said lever and presented thereby in operative relation to said feed drum, and means for operating said lever.
19. In a paper feeding machine, the combination of a supply and feed table having a throat or passageway communicating between them, a feeding drum mounted between said tables at the inner side of said throat or passageway, a ratchet wheel mounted upon said drum, a rock arm carrying a dog which engages said ratchet wheel, a floating lever pivotally connected with said rock arm, a clamp carried by said floating lever, and means for operating said lever, and a U-shaped tappet lever pivotally mounted upon said rock arm and carrying screws which engage said rock arm and said floating lever.
20. In a paper feeding machine, the combination of the supply and feed tables, a feeding drum mounted between said tables, a rocking frame journaled upon the axis of said drum, pawl and ratchet mechanism between said rocking frame and said drum, a shaft upon said rocking frame, a pair of floating levers pivoted upon said shaft, a rod or bar connected with said floating levers, clamping shoes mounted upon said rod or bar supported in operative relation to said feeding drum, and operating means for said connected floating levers.
21. In a paper feeding machine, the combination with curved guides for producing a combing out of a bank of sheets, of means for intermittently clamping said sheets together, said means being movable angularly to correspond with the curvature of said guides, said means comprising a feed roller, a curved clamping jaw and means for simultaneously imparting the same angular movement to said roller and clamp.
